UNITED STATES PATENT OFFICE.

THOMAS W. POWELL, OF FORT WORTH, TEXAS.

DESIGN FOR A BOTTLE.

SPECIFICATION forming part of Design No. 17,700, dated September 6, 1887.

Application filed July 23, 1887. Serial No. 245,149. Term of patent 14 years.

To all whom it may concern:

Be it known that I, THOMAS W. POWELL, a citizen of the United States, residing at Fort Worth, in the county of Tarrant and State of Texas, have invented and produced a new and ornamental Design for Bottles and Similar Receptacles, of which the following is a specification, reference being had to the accompanying drawings, forming part thereof.

10 In the drawings, Figure 1 is a perspective view of my newly-designed bottle or receptacle. Fig. 2 is a side elevation.

15 The leading feature of my invention is a bottle or similar receptacle designed in the configuration of a trunk, or so formed that the outline presented resembles a trunk.

20 In the drawings, A represents the main body of the receptacle, which has the ridges *a*, made to represent the strengthening - straps of a trunk, formed thereon. The upper portion, A', of the receptacle is bulged out slightly at the center and descends in a curved line to the edges, thus conforming to the general contour of a trunk.

25 B represents an opening, shown in Fig. 1 as

formed in the upper portion of the receptacle, and shown in Fig. 2 as formed in the side thereof, it being of course immaterial where the opening is placed so long as the general contour of a trunk is preserved.

30

I claim—

1. The design for a bottle herein described and shown, the same consisting in the bottle or similar receptacle in the form and configuration of a trunk, and having an opening, B, 35 therein.

2. The design for a bottle herein described and shown, the same consisting in the bottle or similar receptacle in the form and configuration of a trunk formed with ridges *a*, and 40 having an opening, B, therein.

In testimony whereof I have hereunto set my hand and affixed my seal, this 7th day of January, 1887, in the presence of two subscribing witnesses.

THOMAS W. POWELL. [L. s.]

In presence of—

JAS. T. EDWARDS,
LEO M. WHITSITT.
